(57) **CLAIM**

The ornamental design for an rechargeable device with flashlight and electronic device charger, as shown and described.

DESCRIPTION

FIG. 1 is a perspective view for an rechargeable device with flashlight and electronic device charger;

FIG. 2 is a front elevational view of the rechargeable device with flashlight and electronic device charger as seen in FIG. 1;

FIG. 3 is a rear elevational view of the rechargeable device with flashlight and electronic device charger as seen in FIG. 1;

FIG. 4 is a left-side view of the rechargeable device with flashlight and electronic device charger as seen in FIG. 1; FIG. 5 is a right-side view of the rechargeable device with flashlight and electronic device charger as seen in FIG. 1; FIG. 6 is a top planar view of the rechargeable device with flashlight and electronic device charger as seen in FIG. 1; FIG. 7 is a bottom planar view of the rechargeable device with flashlight and electronic device charger as seen in FIG. 1;

FIG. 8 is a perspective view for the flashlight;

FIG. 9 is a front elevational view of the flashlight as seen in FIG. 8;

FIG. 10 is a rear elevational view of the flashlight as seen in FIG. 8;

FIG. 11 is a left-side view of the flashlight as seen in FIG. 8;

FIG. 12 is a right-side view of the flashlight as seen in FIG. 8;

FIG. 13 is a top planar view of the flashlight as seen in FIG. 8;

FIG. 14 is a bottom planar view of the flashlight as seen in FIG. 8;

FIG. 15 is a perspective view for the electronic device charger;

FIG. 16 is a front elevational view of the electronic device charger as seen in FIG. 15;

(Continued)

FIG. 17 is a rear elevational view of the electronic device charger as seen in FIG. 15;
FIG. 18 is a left-side view of the electronic device charger as seen in FIG. 15;
FIG. 19 is a right-side view of the electronic device charger as seen in FIG. 15;
FIG. 20 is a top planar view of the electronic device charger as seen in FIG. 15; and,
FIG. 21 is a bottom planar view of the electronic device charger as seen in FIG. 15.
The parts delineated in dashed lines are not part of the claimed design.
